UNITED STATES PATENT OFFICE.

JOHN E. LAWTON, OF BOSTON, MASSACHUSETTS.

LEATHER-FOLDING MACHINE.

SPECIFICATION forming part of Letters Patent No. 285,823, dated October 2, 1883.

Application filed August 9, 1883. (No model.)

To all whom it may concern:

Be it known that I, JOHN E. LAWTON, of Boston, in the county of Suffolk and State of Massachusetts, have invented certain Improvements in Leather-Folding Machines, of which the following is a specification.

This invention is an improvement on leather-folding machines, and refers in particular to the type of such machines as shown in R. H. Lufkin's patent, No. 202,844, dated April 23, 1878, and in order to more clearly show the nature and the value of my improvement I have in my drawings reproduced parts of Lufkin's drawings, and have also shown my improvement as related thereto. As at present constructed, Lufkin's machine acts in the following manner: Parts of shoes which require folding are passed through its mechanism under a knife, which cuts the edge of the leather. The said parts are then carried forward by a foot and a feed-plate, and brought under a folding-presser, which folds the edge and finishes the work ready for stitching. During all this time the cutting operation continues. It now occurs that when parts of shoes, notably the quarters, which consist of two pieces stitched together, are folded by means of the said machine the knife will very often cut into the work when it crosses a seam, and in consequence the seam will be injured and loosened by the knife cutting the thread.

My improvement consists, generally, in means by which I am enabled to suspend the cutting mechanism while the seams of parts, notably in quarters, pass under the knife while the folding operation continues.

It consists, furthermore, in special mechanism to accomplish this result.

In the drawings, Figure 1 represents the cutting and folding mechanism of R. H. Lufkin's patent, No. 202,844, in which H is a shaft which carries the knife b. e is the foot, p the feed-plate, and w the folding-hammer, which assists in the operation.

It will be seen that the knife b is permanently attached to the shaft H, and it becomes clear, upon perusing said Lufkin's patent, that while the folding is going on the cutting mechanism cannot be interrupted.

I will now show in Figs. 2, 3, and 4 how I

accomplish my purpose by means of an attachment which shall take the place of the shaft H, and, without altering the machine any further, will enable me to suspend the cutting while the folding continues.

55

In Fig. 2 is shown an elevation of my attachment. Fig. 3 is a side elevation, and Fig. 4 a sectional view, of the same, like letters representing like parts. A is the shaft which shall replace the shaft H in Fig. 1. This shaft A has a hole, C, and a block, B, is screwed onto the lower end. In the hole C is a movable rod, D, pressed upward by a spiral spring, E, unless prevented by stop S. This stop consists of a lever, which is pivoted at G into the block B, and has a ball-weight at one end, which presses a fork, Z, toward the knife I. The head of the screw F, which holds the knife to the rod D, fits into the fork Z. A knob, K, is joined to the rod D, and moves loosely in the slot T. The spiral E is fixed to the shaft by means of the screw M.

60

The operation is as follows: The normal condition is illustrated in Fig. 2. The knife I is held firmly, because it is prevented from sliding upward by the fork Z, which has caught the head of screw F. As soon, however, as a seam in the quarter is about to be shifted by the machine under the knife I the operator presses on the knob K with the forefinger, and, having relieved the spring-pressure from the stop-fork Z, the thumb is placed against the ball of lever S, the fork is moved thereby away from screw F, and the rod D, with the knife, slides upward, and the material, or rather the seam, can pass through without being cut. This position is shown in Fig. 4, and the folding mechanism not being affected, the folding of the material continues. After the seam has passed beyond the knife the operator merely presses down the knob K, moves the screw F beyond the fork Z, when the fork will again catch in over the screw F by means of the ball-weight, and thereby fix the rod and the knife into normal position, (shown in Fig. 2,) ready for again resuming the operation of cutting.

70

I claim—
1. In a leather-folding machine, the knife I, in combination with the mechanism, substan-

100

tially as described, for the purpose of rendering the said knife inoperative while the folding continues, as set forth.

2. In a leather-folding machine, the combination of rod D, knife I, with pin or screw F, and stop Z, substantially as described.

3. In a leather-folding machine, the press-knob K, in combination with rod D and knife I, substantially as and for the purpose set forth.

In testimony whereof I have signed my name to this specification, in the presence of two subscribing witnesses, this 7th day of August, 1883.

JOHN E. LAWTON.
